TIMER MECHANISM

Glenn Morse, Ann Arbor, Mich., assignor to King-
Seeley Corporation, Ann Arbor, Mich., a cor-
poration of Michigan

Application August 17, 1945, Serial No. 611,115

1 Claim. (Cl. 161—1)

1

The present invention relates to timing devices employing clock movements, and is particularly directed to the provision of improved arrangements for maintaining such movements at rest in various rotative positions of the associated main arbor and for insuring proper starting thereof. An illustrative application of the invention is in connection with timers for use in connection with stoves, washing machines, and other appliances.

Principal objects of the present invention are to provide timing mechanisms of the above indicated types, which are simple in arrangement, economical of manufacture and assembly, and which are reliable and efficient in operation; to provide such timers employing an escapement mechanism, and further employing improved control means for cooperating with the escapement mechanism to hold it at rest in desired positions and to also cooperate therewith in insuring the proper starting thereof; to provide such mechanisms wherein the escapement mechanism is of the so-called verge type, and wherein the control means comprises one or more resilient elements which cooperate with the verge arm to hold the escapement at rest in various positions of the associated main arbor, such, for example, as the so-called starting and fully wound positions, and wherein said resilient elements also cooperate with the verge arm to insure the proper starting of the escapement mechanism; to provide such mechanisms wherein the control means is actuated in response to the movement of the main arbor; and to generally improve and simplify the construction and arrangement of mechanisms of the above type.

With the above as well as other and more detailed objects in view, which appear in the following description and in the appended claims, a preferred but illustrative embodiment of the invention is shown in the accompanying drawings, throughout the several views of which corresponding reference characters are used to designate corresponding parts and in which:

Figure 1 is a view in front elevation of a timer embodying the invention;

Figure 2 is a view in side elevation of the structure of Figure 1;

Figure 3 is a view, taken along the line 3—3 of Figure 2;

Figure 4 is a view corresponding to Figure 3, with the bell removed;

Figure 5 is a view in rear elevation of the structure of Figure 1, with the cover removed, taken along the line 5—5 of Figure 7;

2

Figure 6 is a view in front elevation of the timer movement, taken along the line 6—6 of Figure 7, showing the parts in one of two possible starting positions;

5 Figure 7 is a view in section, taken along the line 7—7 of Figure 6, which, it will be noted, extends through all of the axes of the movable elements of the timer movement;

Figure 8 is a fragmentary view of certain of the 10 escapement elements and of the cooperating control means, showing the normal running positions thereof;

Figure 9 is a fragmentary view, based upon 15 Figure 7, and showing the parts in another possible starting position;

Figure 10 is a fragmentary view, based upon 20 Figure 7, and showing the parts in the so-called "fully wound" position;

Figure 11 is a fragmentary view, partly in section, taken along the line 11—11 of Figure 10; and,

25 Figure 12 is a fragmentary view, taken along the line 12—12 of Figure 10.

It will be appreciated from a complete understanding of the present invention, that, in a generic sense, the improvements may be embodied in a wide variety of timing devices, intended for widely differing applications. As mentioned above, a preferred but illustrative application of 30 the invention is in connection with so-called stove timers, washing machine timers, and the like.

In such timers, the clock movement is normally maintained at rest at a so-called starting position. A winding means, such as a knob, is usually provided which may be turned in one direction through all or any desired part of a full revolution, during which movement the main spring is wound. Except as noted below, upon release of the winding means, the clock movement drives the main arbor in a reverse direction until the starting position is reached, at which time the movement is again automatically brought to rest. At the starting position also, suitable "signal" means may be actuated. For example, the "signal" means 45 may take the form of an electric switch, a bell, or other instrumentality and consequently the term "signal means" is used herein in a generic sense as referring to any instrumentality which responds to a predetermined degree of arbor movement. In certain cases also, it is desired to 50 arrange the structure so that it will remain at rest in the fully wound position in which, for example, it may hold a signal means such as an electric switch in desired closed or open position.

55 The present invention is particularly directed

to the provision of improved means for stopping the timer movement at desired positions, such as the starting and fully wound positions and for also insuring the proper starting of the timer mechanism. Since the elements which particularly characterize the present invention can be utilized with any of a variety of general timer constructions, the herein illustrated general timer mechanism will only be briefly described.

Referring to the drawings, the present construction comprises a movement 20 which is disposed within a substantially sealed enclosure comprising a cup-shaped base member or housing 22 and a cover member 24, which serves as a housing for the main spring 26 and is referred to hereinafter as the spring housing. The movement 20 comprises front and back movement plates 28 and 30, which are held in assembled relation to each other by a plurality of circumferentially spaced posts 32. Posts 32 project outwardly from the movement plates 28 and 30, and are received in openings provided therefor in the housing 22 and the spring housing 24. Nuts 34 serve to hold the housing 22 in place relative to the posts 32, and nuts 36 serve to secure the spring housing in place. Suitable means, such as the gasket 38, serve to seal the joint between the marginal edges of members 22 and 24.

In the illustrated instance, the signal mechanism is a bell 40, which is adapted to be sounded when, in the course of a return movement, the main arbor 42 reaches the starting position. The bell 40 is carried by the spring housing 24, and is secured thereto by means of a set of circumferentially distributed studs 46, which are threaded into tapped openings provided in outwardly projecting bosses 48. With this relation, the main body of the bell is spaced from the spring housing.

The arbor 42 projects through the base of the bell, and, at its outer end, 43, is adapted to releasably receive a usual knob 50.

The spring housing 24 is provided with an additional pair of tapped openings 52, which receive screws for securing the timer to a suitable mounting plate (not shown), the face of which may be provided with graduations with which the pointed end of the knob 50 cooperates. With reference to Figure 1, a winding action is effected by turning knob 50 in a clockwise direction, the unwinding or timing movement being effected by enabling the clockwork or movement 20 to effect a counterclockwise travel of the arbor 42 and knob 50, back to the indicated starting position.

In order to initially adjust the mechanism so that the tripping point, at which bell 40 is sounded, and at which the timer movement is stopped, shall accurately correspond to the zero reading of the knob 50, provision is preferably made to rotatably adjust the spring housing 24 relative to the movement 20. As shown, spring housing 24 is provided with elongated slots 56, which adjustably receive the previously mentioned posts 32, and which permit the aforesaid adjustment.

Referring now more particularly to the movement 20, the arbor 42 is rotatably supported in bearings provided therefor in the front and rear movement plates 28 and 30. Externally of the movement plate 28, the arbor 42 is fixedly connected to one end of the main spring 26, the other end whereof is keyed to the spring housing 24. Arbor 42 is connected, through a ratchet or one-way clutch 60, and a train of gears 62 which includes a friction clutch 66, to an escapement mechanism 64 of the well-known verge type. The ratchet clutch 60 may be conventionally

arranged and does not require a detailed description except to note that it permits a winding movement of the arbor 42 and of the main spring, without requiring a movement of the gear train, but causes an unwinding movement of the arbor to drive the gear train. In the drawings, a winding movement of the arbor corresponds to clockwise movement thereof as viewed in Figures 4 and 6.

With the foregoing arrangement, it will be appreciated that the knob 50 may be turned in a clockwise direction as viewed in Figure 1 throughout all or any desired fraction of a complete revolution, during which movement the main spring loading is increased from the initial or minimum value to a correspondingly higher value. Neglecting the full-wind holding feature, which is described below, release of the knob 50 enables the main spring 26 to drive the arbor 42 in a counterclockwise direction as viewed in Figures 4 and 6. During the course of this unwinding movement, the arbor 42 drives the gear train, the rate of movement of which is controlled by the escapement mechanism 64, which consequently serves to control the rate of the arbor movement. A rapid reset movement may be effected by turning the handle 50 in a counterclockwise direction, in which event the clutch 66 slips.

The verge type escapement comprises, in accordance with conventional practice, a toothed escape wheel 70, a verge arm 72, a balance staff 74, a balance wheel 76, and an adjustably mounted balance spring 78. The verge arm 72 is provided, adjacent its lower end, with a pair of impulse pins 80 and 82 which cooperate with the teeth of the escape wheel 70. At its upper end, the verge arm 72 is provided with a slot 84, which cooperates with the usual roller pin 86 which is carried by the balance wheel 74. Further in accordance with conventional practice, the balance staff 74 is provided with a notch 88, which permits the verge arm portions 90 and 92 to pass back and forth from one side to the other of the line which connects the verge arm and balance staff axes. Finally, the verge arm is provided with stop portions 94 and 96 which serve to provide positive, but only infrequently encountered, limits to the swinging movements of the verge arm.

In further accordance with conventional practice, the present timer mechanism includes cocking means which is actuated at the beginning of each winding movement, and which is tripped at the conclusion of each unwinding movement. In the present embodiment, the signal mechanism consists of a bell, which is to be sounded at the conclusion of each unwinding movement. Consequently, the cocking action serves to prepare the bell hammer for operation, and the tripping action serves to actuate the hammer mechanism and sound the bell. In case it is desired to utilize switch mechanism, the cocking action may, of course, be utilized to either open or close the switch, and the tripping action may be utilized to effect a reverse operation of the switch. In accordance with the present invention, the cocking mechanism is also utilized, as described below, to control the automatic stopping of the timer movement at the starting position, the holding thereof at the fully wound position, and the automatic starting thereof at the beginning of each unwinding movement.

More particularly, in the illustrated embodiment, the cocking mechanism comprises a cam assembly which includes a cocking cam 100 and a holding cam 102. The cocking cam 100 is driv-

ingly carried by the arbor 42, and is held in place thereon by a snap ring 104. The holding cam 102 is carried by the cam 100 and is pivotally connected thereto by means of a pin 106. Spring 108, having its respectively opposite ends anchored to cams 100 and 102, continuously urges the latter in a counterclockwise direction as viewed in Figure 5. A limit to such movement is afforded either by engagement of the cam shoulder 110 on cam 102, with the pin 112, which is carried by the hereinafter described hammer lever 114, or, by engagement of the inwardly turned flange 116, on cam 102, with the surface 118 on cam 100. Cam 100 is provided with a peripheral notch, one side of which is constituted by the surface 118 and the other side of which is constituted by the gradually sloping surface 120. In turn, cam 102 is provided with a notch, both sides 110 and 116 of which are rather sharply inclined.

The hammer lever 114 is of bell crank form, one arm 122 whereof carries the previously mentioned pin 112, and the other arm 124 which cooperates with the hammer 126. Hammer lever 114 and hammer 126 are both carried by a shaft 130, which has bearing support in the movement plates 28 and 30. Hammer lever 114 is drivingly connected to shaft 130, and hammer 126 is loosely mounted thereon. A tension spring 132, one end whereof is hooked over the hammer lever arm 122, and the other end whereof is anchored to the rear movement plate 30, continuously urges the hammer lever in a counterclockwise direction as viewed in Figure 6, which corresponds to a clockwise direction as viewed in Figure 5. This action holds the hammer lever pin 112 (which projects outwardly through a slot 136 in the rear movement plate 30) at its inner limit, in which it abuts the base of the notch in the cam 100. A spring 140 surrounds shaft 130 and has its respective ends 141 and 143, respectively, anchored to the hammer 126 and to the hammer lever arm 124. Spring 143 thus continuously urges hammer 126 to the positions shown in Figures 6 and 10, in which one side thereof abuts a flange 144 which is provided on the arm 124 of the hammer lever. A clockwise or cocking movement of the hammer lever 114, as viewed in Figures 6 and 10, enables spring 140 to correspondingly swing the hammer 126 in a clockwise direction to a cocked position. To insure such a cocking movement, arm 124 is provided with an additional flange 146.

In the present instance, since the hammer 126 is mounted within the enclosure constituted by the housing members 22 and 24, and since the bell 40 is mounted externally thereof, an intermediate connection is utilized between the hammer 126 and the bell 40. More particularly, this intermediate connection comprises a spring pressed button 150 which is received in an opening provided therefor in the housing 22, and is continuously urged to the retracted position shown in Figure 6 by means of a compression spring 152. In such position, button 150 seals off the just-mentioned opening. A sounding movement of the hammer serves to drive button 150 outwardly into engagement with the bell 40, against the force of the spring 152.

In accordance with the present invention, the shaft 130 also carries a pair of relatively light spring wires 160 and 162, which are clamped in place thereon between collars 164 and 166. Collars 164 and 166 are press fitted on shaft 130.

In the normal or starting position of the timer,

wires 160 and 162 occupy either the position shown in Figure 6, or the alternative position shown in Figure 9, depending upon the character of the stopping action as described below in connection with the operation of the device. In the position shown in Figure 6, the end of wire 160 lies behind the stop surface 94 on the verge arm 72, and holds it at an intermediate, approximately central, point in its stroke, in which the verge pin 80 lies in blocking relation to a tooth of the escape wheel 70. In the alternate stopping position of Figure 9, the end of wire 160 rests upon the upper surface of the holding portion 94 of the verge arm 72 and, being stressed in such position, is effective to hold the verge arm 72 at or slightly beyond the normal right-hand limit of the swing of the verge arm 72. In this position, the verge pin 82 lies in blocking relation to a cooperating tooth of the escape wheel assembly and prevents movement of the latter.

In the normal running position of the timer, shown in Figure 8, wires 160 and 162 are disposed outside of the path of the verge arm, and do not interfere with normal movements thereof. In the fully wound position of the timer, shown in Figure 10, the end of wire 162 lies behind the holding surface 94 of the verge arm 72, and holds it at an intermediate point in its stroke, which blocks movement of the escape wheel 70 in the manner described in connection with Figure 6. The movement of wire 162 from the running position of Figure 8 to the holding position of Figure 10 takes place as a consequence of an added rocking movement of the hammer lever 114, which occurs at the completion of the winding movement, as is described below.

It is believed that any remaining pertinent details of the present timer may best be understood from a description of the operation thereof.

As previously mentioned, the parts are shown in the normal or starting positions thereof, in which the wire 160 occupies one or the other of the stopping positions shown in Figures 6 and 9. To place the timer in operation, knob 50 may be turned in a clockwise direction as viewed in Figure 1 throughout a desired portion of the full range. Such winding movement winds the main spring 26, but, by virtue of the ratchet clutch 60, does not cause a movement of the gear train. If it is desired to immediately reset the timer, knob 50 may be manually returned in a counterclockwise direction to the starting position. This movement is permitted, at a rate in excess of the escapement rate, by virtue of the friction clutch 66, which is interposed in the gear train 62.

The initial winding movement of the arbor 42 causes cam 103 to rotate in a counterclockwise direction as viewed in Figure 5, during which movement roller 112 of the hammer lever 114 is cammed radially outwardly by the cam surface 120. Until such a time as roller 112 has moved radially outwardly far enough to clear the notch in the holding cam 102, the latter is forced, by the sharp shoulder 110 thereof, to rotate in a clockwise direction, about the pin 166, which is bodily moving with cam 100. Such relative movement loads the return spring 168. As soon as the winding movement of the arbor has progressed sufficiently far to clear the end of the cam surface 110, by which time the roller 112 is completely out of the notch in cam 100 and is riding on the cylindrical surface portion thereof, spring 108 is enabled to restore cam 102 to

the position, relative to cam 100, which is shown in Figure 5. In such position, the peripheral surface 111 of cam 102 also lies below and in supporting relation to roller 112. As shown, the peripheral surface 113 of cam 100 projects slightly outwardly from the peripheral surface portion 111, so as to insure that spring 106 can effect the just-mentioned return movement of cam 102.

The cocking movement of the hammer lever 114, described above, also effects the previously mentioned cocking movement of the hammer 126, and also rotates shaft 130, swinging wires 160 and 162 to the running position shown in Figure 8, the movement of wire 162 being without effect in the operation now being described. Assuming that wire 160 initially occupied the position shown in Figure 6, such movement thereof obviously imparts a swinging movement to the verge arm 72, enabling it, under the influence of the balance spring, to oscillate back and forth. Assuming, on the other hand, that wire 160 initially occupied the holding position shown in Figure 9, such movement thereof to the running position of Figure 8, enables the now fully loaded balance spring to initiate a swinging movement of the verge arm. In either instance, therefore, the cocking movement of the hammer lever enables spring 160 to impart a starting impulse to the verge arm 72, as a consequence of which it makes a succession of oscillations.

It will be understood that preferably the main spring 26 is partially loaded when the parts are in the starting position. This initial loading, plus the additional loading which results from turning the knob 50 through even a relatively small fraction of a complete revolution, enables the main spring to apply sufficient torque, through the escapement wheel, to start the escapement as soon as the knob 50 is released at the conclusion of the starting movement. Abnormal circumstances may introduce sufficient frictional losses into the gear train to reduce the torque applied by the escapement wheel to the verge arm, following short winding movements, to too low a value to effect a starting of the escapement. Such circumstances are taken care of by the above-mentioned starting impulse. That is to say, the above-mentioned starting impulse is found to cause the verge arm to oscillate sufficiently long that it is still in motion at the conclusion of a short winding movement. Being in motion, the escapement readily causes the unwinding movement to begin as soon as the knob 50 is released.

On the other hand, if the winding movement of the knob 50 is continued through a sufficiently large angle as to enable the verge arm to come to rest, following the starting impulse, such winding movement loads the main spring sufficiently to insure that sufficient starting torque is available at the escapement wheel.

Release of the knob 50, of course, enables main spring 26 to drive the main arbor and the gear train 62 at the rate determined by the escapement mechanism, during the course of which return movement cams 100 and 102 rotate in a clockwise direction as viewed in Figure 5. As the arbor approaches the starting position, the sloping surface 120 of cam 100 comes into registry with the pin 112 of the hammer lever 114, rendering cam 100 ineffective to hold the lever 114 in the cocked position. At this time, however, cam 102 is effective to maintain lever 114 in the cocked position.

When the starting position is reached, the notch in the cam 102 comes into registry with pin 112, and enables the return spring 132 to promptly snap lever 114 from the cocked position to the normal position. During this return movement of the hammer lever, flange 144 thereon, causes a corresponding rapid outward swing of the hammer 126, during the course of which it strikes the button 150, and causes it to strike the bell 40, sounding the latter. A limit to the swing of the hammer 126 is afforded by the flange 146, on the hammer lever, and the hammer is also quickly restored to its normal position by its spring 140. The button 150 is also promptly returned to its normal position by its spring 152.

The return movement of the hammer lever 114 also moves wires 160 and 162 towards their starting positions. It will be noticed that the path of travel of the end of wire 162 intersects the path of travel of the verge arm holding surface 94 at a point which is relatively near the normal right-hand limit of movement of the latter. In its swinging movements, accordingly, the holding surface 94 is out of range of the wire 162 a major part, for example, 75%, of the time. In a correspondingly major proportion of cases, accordingly, wire 160 is enabled to move to the stopping position shown in Figure 6, in which it prevents completion of the next rightward swing of the verge arm 72 and consequently stops the timer movement. In the remaining instances, holding surface 94 is in the path of movement of wire 160 during the return movement of the latter, and wire 160 consequently comes to rest in stopping position shown in Figure 9, in which it prevents a leftward swing of the verge arm 72. In either event, the tripping movement of the hammer lever, is effective, through the wire 160, to promptly bring the timer movement to rest. With such arrangement, the knob 50 always stops at the bell sounding position, which, by virtue of the adjustment permitted by slots 56 (Figure 4), may readily be caused to correspond accurately with the zero point of the associated timer dial 54 (Figure 1). In addition to its self-starting function, accordingly wire 160 serves as an automatic stopping means for the timer movement.

Considering now the fully wound feature of the invention, it will be noticed from Figure 5, that if the winding movement is continued through the substantially full 360 degrees of movement, cams 100 and 102 are carried around sufficiently far, in a counterclockwise direction relative to pin 112, to bring the concave surface 115 on cam 102, into engagement with pin 112. Continued winding movement causes cam 102 to rotate in a clockwise direction, relative to cam 100, about pin 106, during the course of which movement the concave surface 115 moves radially outwardly relative to the arbor 42, and carries pin 112 to an outer limit position, which is defined by the engagement of an outwardly turned flange 147, on lever 114, with the side of an associated slot 119 which is provided in the rear movement plate 30. Such engagement affords a positive mechanical limit to the winding movement.

In accordance with the present invention, this additional movement of the hammer lever 114 also serves to block movement of the escapement mechanism. More particularly, such final movement swings wire 162 from the running position of Figure 8 to the fully wound or stopping position of Figure 10, in which the end of wire 162 lies behind and in blocking relation to the hold-

ing portion 94 on the verge arm 72. Release of the knob 50 at the fully wound position, accordingly, does not initiate an unwinding movement, since the escapement mechanism is blocked. As will be understood, the final movement of the hammer lever may also be used to operate additional instrumentalities, such as switches, bells, or the like.

To initiate an unwinding movement from the fully wound position, knob 50 may be manually turned in a counterclockwise direction, as viewed in Figure 1, through a small angle, sufficient to cause the surface 115 on cam 102 to clear the hammer lever pin 112. Such return movement, which is permitted by virtue of the clutch 66, enables the hammer lever pin 112 to swing back to the normal cocked position, in which wires 160 and 162 occupy the running position shown in Figure 8.

Although only a single specific embodiment of the invention has been described in detail, it will be appreciated that various modifications in the form, number, and arrangement of the parts may be made without departing from the spirit and scope of the invention.

What is claimed is:

In a timing device, an arbor, a main spring for

driving said arbor, escapement mechanism for controlling the rate of movement of the arbor, winding means for winding said main spring in preparation for a said driving movement, and control means responsive to a predetermined degree of said winding movement and engageable with said escapement mechanism for blocking movement thereof, whereby to prevent a said driving movement of said arbor, said escapement mechanism being of the verge type including an oscillatory arm, and said control means including a flexible element which is engageable with said arm.
